FOLDABLE BOX

Guy J. Evans, Buffalo, N. Y.

Application May 1, 1943, Serial No. 485,328

1 Claim. (Cl. 229—42)

This invention relates to a folding box and more particularly to a box of this character having a container, a cover adapted to close the top of the container and a partition whereby the interior of the container is divided into a plurality of cells or compartments.

The objects of this invention are to provide a folding box which requires a minimum of material and can be manufactured economically, which can be quickly and easily assembled, which permits of reliably interlocking its parts so that the same are strong and durable and will not come apart when used, which enables the cover to be conveniently and easily applied to the container without liability of interference of the container with the fastening means of the cover, and in which the partition is so constructed that it consumes a minimum of material and its parts are firmly interlocked when erected into operative position.

In the accompanying drawings:

Fig. 1 is a side elevation of an erected folding box embodying this invention.

Fig. 2 is a vertical longitudinal section of the same taken on line 2—2, Fig. 3.

Fig. 3 is a vertical cross section of the same taken on line 3—3, Fig. 2.

Fig. 4 is a plan view of a flat blank from which the container is made.

Fig. 5 is a similar view of the flat blank from which the cover is made.

Fig. 6 is a similar view of the flat blank from which one section of the partition is made.

Fig. 7 is a perspective view of the completely erected container embodying this invention.

Fig. 8 is a fragmentary perspective view of a partly erected container.

Fig. 9 is a perspective view of a completely erected cover embodying this invention.

Fig. 10 is a fragmentary perspective view of a partly erected cover.

Fig. 11 is a fragmentary perspective view of a partly erected partition section containing the improvements of this invention.

In the following description the same reference characters indicate corresponding parts in the several figures of the drawings.

The several members of this box are preferably made of cardboard or stiff paper, but if desired the same may be constructed of any other suitable sheet material which can be die cut into the form of a flat blank and bent into the required shape.

The flat blank of cardboard or other sheet material from which the body or container of the

box is formed or erected, as shown in Fig. 1, comprises a bottom panel 20 of rectangular form, two rectangular side walls 21, 21 arranged on opposite sides of the bottom panel and adapted to be folded upwardly thereto into an upright position along scored longitudinal folding lines 22, 22 between the opposing edges of these parts. At opposite ends of the bottom panel are arranged the transverse end walls 23 of the container blank 10 which are adapted to be turned into a position relative to the bottom panel along scored transverse folding lines 24, 24 between the opposing transverse edges of these parts. Each of these end walls is equal in height to the side walls so that when the side and end walls are turned upwardly the upper edges of the same are even.

Alongside of the transverse edges of each side wall are arranged rectangular retaining flaps 25 each of which is adapted to be folded into a position at right angles to the plane of the respective side wall along a scored line 26 between the same, and each of these flaps being equal in height to that of the side and end walls but the width of the same is one-half that of the bottom panel and end walls so that when the flaps at the corresponding ends of the two side walls are folded at right angles thereto the free inner edges 27 of these flaps will be opposed and engage one another.

On opposite sides of the center of the outer edge of each end wall the same is provided with two locking hooks 28 each of which has its inner edge 29 undercut to form an inwardly overhanging beak 30 while the outer edge 31 of this hook 35 inclines inwardly.

Each of the flaps 25 is provided adjacent to its upper edge with a V-shaped locking slit one part or branch 32 of which is horizontal and parallel with the upper edge of the respective flap while the other part or branch 33 of the same inclines at an acute angle downwardly and laterally relative to the horizontal branch of this slit.

When operating the body blank for the purpose of converting the same into a container the side walls 21 are first turned upwardly along the lines 22 into a perpendicular position relative thereto together with the flaps at opposite ends of the side walls. Then the flaps are turned inwardly on the lines 26 so that the flaps at corresponding vertical edges of the side walls meet midway of the width of the container. The end walls are now turned upwardly along the lines 24 into an upright position so that each end wall bears against the outer sides of the adjacent pair of flaps 25 of the side walls. While in this position

tion each of the locking hooks 28 is slipped inwardly and upwardly through the horizontal upper part 31 of the respective retaining flap 25 and the incline 29 of the undercut side of the beak at the inner edge of the locking hook is engaged with the extremity of the inclined branch 33 of the locking slit. In order to thus engage the beak of each locking hook with the locking slit of the respective retaining flap it is necessary to spring the respective flap and hook slightly relative to one another, but after the inclined undercut sides of the beaks of both locking hooks have been engaged with the extremities of the inner branches 33 of the respective locking slits at one end of the container, the lateral pull on the locking hooks, due to the resilience or tension of the bent side walls, causes the undercut inclined edges of the locking hooks to be drawn tightly against the extremities of the inclined inner parts of the locking slits and hold the walls of the container firmly in an erected position. The act of passing the locking hooks through the locking slits and interlocking the hooks and flaps can be effected manually very easily and quickly and thus materially reduces the cost of the doing this work and at the same time producing a container which is very rigid and not liable to be deformed by ordinary usage. When the container is completely erected the central part of each end wall has its upper edge arranged on a level or even with the upper edges of the respective flaps and the upper ends of the locking hooks are arranged below the level of the upper edges of the flaps.

It will be noted that in the erected condition of the container the several locking hooks of the end walls when interlocked with the locking slits of the flaps have their beaks turned downwardly, whereby these hooks are not liable to be disengaged from these slits when depositing anything in the container. This arrangement of the hooks also causes the inclined undercuts of their beaks to act as wedges and produce a transversely inward pull on the end and side walls and maintain the container in a rigid condition.

The flat blank, shown in Fig. 2, of cardboard or other sheet material from which the cover of the folding box is made comprises a rectangular top panel 34, two longitudinal side flanges 35 arranged on transversely opposite sides of the top panel and each adapted to be turned downwardly into a position perpendicular to the latter along a scored longitudinal line 36 between the same, and two transverse end flanges 37 arranged at longitudinally opposite ends of the top panel and each adapted to be turned downwardly at right angles to the top panel along a scored transverse line 38 between the same.

Locking means are provided whereby the adjacent ends of the several side and end flanges are connected with each other at the respective corners of the cover each of which locking means being constructed as follows:

Adjacent to each end of the side flanges the same is provided with a V-shaped locking slit the parts or branches 39, 40 of which converge upwardly or toward the top of the cover and also toward the corner of the box and said parts of each locking slit forming an acute angle between them.

The numeral 41 represents locking hooks one of which projects laterally from each end of the transverse cover flange and is adapted to be turned at right angles thereto on a line 42 be-

tween the same. At its outer end each of the locking hooks is provided with a beak 43 having an undercut recess 44 which opens upwardly or toward the top of the cover when the latter is erected. After the side and end flanges have been bent or folded downwardly relative to the top of the cover each of the locking hooks is bent relative to its companion end flange and then its beak is passed upwardly through the locking slit in the adjacent end of the respective side flange and the upwardly opening undercut recess of this beak is engaged with the corner between the two parts of the V-shaped locking slit, thereby locking together the adjacent ends of the respective side and end flanges. Due to the resilience of the sheet material of which the cover is constructed, a pull is exerted on the beaks of the locking hooks whereby the same are held in tight engagement with the corners of the V-shaped locking slits and thus renders the cover strong and stiff and not liable to get out of shape. By constructing the corner locking means of the cover so that the beaks and undercut recesses of the locking hooks are toward the top of the cover, instead of downward therefrom, a much more reliable connection is produced between the side and end flanges at each corner of the cover and any obstruction which may be met by the locking hooks when applying the cover to the container will not tend to unfasten the same but on the contrary will serve to interlock the locking hooks and slits more effectively.

When the cover is applied to the container for enclosing the goods in the latter the flanges of the cover surround the upper parts of the walls of the container as usual in boxes of this character, the overall dimensions of the cover being somewhat greater than those of the container for this purpose. If, upon closing the cover over the container, any of the goods within the same should come in contact with any of the locking hooks of the container or the cover, these hooks would be pushed outwardly, those of the cover toward the top thereof and those of the container toward the bottom of the same, and thereby tend to engage these hooks more securely with the slotted members cooperating therewith. If the beaks of these locking hooks were turned toward the inner side of the box, as has been the case heretofore, any engagement of goods in the box with these hooks would be liable to push the same out of the slits with which they engage and thus loosen the box and render the same insecure as an enclosure for the goods. It will therefore be apparent that turning the beaks of the locking hooks on the container and cover outwardly toward the surface of the box avoids the liability of disengaging the hooks from the slotted members and thus maintains the box in a strong and durable condition so as to provide the best protection for the goods enclosed in the box.

The space within the box is divided by a partition into a plurality of cells or compartments which are adapted to receive individual goods and separate the goods in adjacent compartments from one another. This partition comprises a plurality of sections which may be assembled so as to produce a group of compartments in one plane, or the same may be assembled so that a series of groups of compartments are stacked or superposed one above another. In Figs. 2 and 3 the partition sections are arranged to form two superposed groups of compartments, as an example of one use of this invention, but it is to be

understood that the invention applies to a single group or more than two groups of compartments.

Each section of the partition is made of cardboard or other sheet material, and is formed from a flat blank which, as shown in Fig. 6, comprises two rectangular strips 45, 46 which are adapted to be bent or folded relative to each other along a scored longitudinal line 47 so that the strip 45 forms a horizontal flange and the strip 46 a vertical flange which projects upwardly from one longitudinal edge of the horizontal flange, as shown in Figs. 2, 3 and 11. At intervals the horizontal flange 45 is provided with alternating slits 48, 49, each slit 48 extending in at right angles fully from the edge of the lower horizontal flange 45 to the folding line 47 between the same and the vertical flange 46, and the slit 49 extending at an oblique angle from said folding line toward the outer edge of said horizontal flange for a distance about one-fourth of the width of the horizontal flange. At intervals in its length the blank of the partition is provided along the longitudinal folding line 47 with short longitudinal slits 50 each of which extends from the inner end of one of the right angle slits 48 to the inner end of an adjacent oblique slit 49 so that the respective slits diverge from the folding line 47 toward the outer edge of the horizontal flange.

At intervals the horizontal flange of the partition blank is provided with scored transverse folding lines 51 each of which extends from the outer end of one of the oblique slits 49 to the outer edge of the respective horizontal flange, thereby dividing the latter into a plurality of cell bottoms 52 and a plurality of cross walls 53 which alternate with the cell bottoms. By bending the strip 46 upwardly relative to the strip 45 along the longitudinal line 47 and bending each of the walls 53 upwardly into a vertical position along the respective transverse line 51, a plurality of cells are produced of which the horizontal parts 52 form the bottoms, the upright parts 53 form the transverse walls and the upright part 46 forms the longitudinal walls of the several cells. When the partition blank is thus bent each of the bottoms 53 is mainly rectangular in form but provided adjacent to the respective oblique slit 49 with a triangular projection forming a gusset 54 and the adjacent corner of the respective cross wall 53 from which this gusset has been formed is blunt or cut off as shown at 55 in Figs. 3, 6 and 11. The presence of this gusset between the upright longitudinal wall 46 and each of the cell bottoms strengthens this partition section as a whole but the blunt formation 55 at the inner lower corners of the cross walls of the cells does not weaken the same.

Locking means are provided whereby the cross walls of the partition sections are held in a vertical position, which means are constructed as follows:

The numeral 56 represents a plurality of locking tabs each of which is arranged on the inner edge of one of the cross walls 53 and adapted to interlock with the vertical end of a resilient locking tongue 57 on the adjacent part of the respective longitudinal partition flange. The locking tab is preferably inclined downwardly and formed by means of a U-shaped slit 58 out of the lower edge of the longitudinal flange 46 between a pair of adjacent slits 48 and 49 in the respective partition blank. Each of the locking tongues 57 is preferably inclined toward the adjacent slit 50 of the partition blank and formed

by means of a correspondingly shaped slit 59 formed from the material or stock in the longitudinal flange of the partition blank and having a vertical front edge, as shown in Figs. 2, 6 and 11. When forming each partition section the longitudinal strip 46 is first turned into an upright position relative to the companion horizontal strip of the partition section and then each of the cross walls is raised from the horizontal position in which it was cut from the blank to a vertical position in which it forms part of a cell. While thus raising each cross wall into an upright position the locking tab 56 thereof rides over the respective locking tongue 57 and deflects the same until the tab reaches the vertical front end of the tongue and then the latter will spring back, due to its inherent resilience, and engage the rear side of the tab with a clutch action, whereby this cross wall and the upright flange of the partition section are securely interlocked and the parts of the same are securely held in their operative position.

When a plurality of partition sections are arranged side by side in the box the vertical longitudinal flange of a section on one side of the box engages with the corresponding side wall of the box while the opposite wall of the box forms a closure for the open outer sides of the cells on the opposite side of the box, and those cells whose open sides face inwardly are closed by the vertical longitudinal flanges on an adjacent partition section.

In Figs. 2 and 3 two partitions are arranged side by side in the lower part of the box and the height of the latter is such that two groups of partition sections can be placed one above the other in the box, but this number of partition sections and groups may be varied to suit requirements.

It will be noted that some of the cell bottoms are comparatively short and others long and this can also be varied as desired.

As a whole this folding box is very simple in construction, the same can be manufactured from a minimum amount of material, its erection can be accomplished with ease and facility so that the cost is low, and in its completed form the same provides a box in which the corners are securely locked and thus render the same very strong and durable, neat in appearance and not liable to be distorted while being handled or shipped.

The partition whereby the interior of the box is subdivided in a plurality of cells permits of utilizing the sides and ends of the container of the box to form walls of these cells and thus effecting a saving in material and also the time required to assemble this unit in the container.

I claim as my invention:

A folding box including a partition which divides the interior of the box into a plurality of cells, said partition comprising a section formed from a flat sheet blank having two longitudinal strips which are adapted to be turned relative to each other on a longitudinal line so that one of said strips forms a horizontal flange and the other a vertical flange, and said blank being slotted at intervals along said longitudinal line and said horizontal flange being slotted at intervals from its outer edge to said longitudinal line to provide a plurality of cross walls which are bent upwardly relative to said horizontal flange and divide parts of the latter into a plurality of cell bottoms, and locking means for connecting each of said cross

walls with said upright flange and holding said cross wall in an upright position, including a hook shaped locking tab arranged on the upright inner edge of said cross wall and inclining downwardly therefrom in the form of a beak which is adapted to engage with the outer side of said vertical flange and formed by material removed from the lower edge of said vertical flange, and a flexible locking tongue which is free at its front end and at its opposite sides and attached at its rear end to said upright flange and formed in this flange by cutting a U-shaped slot therein, and this flexible locking tongue being deflectable by moving engagement therewith of the front end of said locking tab and said locking tongue being engaged at its front end by said locking tab when

said cross wall is in a vertical position, and said locking tongue being arranged at an angle which is tangent to the curve of the axis about which said cross wall turns when the same moves from a position co-planar with said horizontal flange to a position at right angles thereto, and the inner lower corner of each cross wall being cutoff at an angle and the material of said cutoff portion being left in the adjacent part of the horizontal flange to form a V-shaped gusset between the inner edge of the respective portion of the horizontal flange and the adjacent lower edge portion of the vertical flange for increasing the strength of the connection between these flanges.
